LUMINAIRE

Myron F. Pettengill, Hendersonville, N.C., assignor to
General Electric Company, a corporation of New York

Filed Apr. 20, 1962, Ser. No. 69,782

Term of patent 14 years

(Cl. D48—31)

FIG. 1 is a side elevational view of a luminaire embodying my new design;

FIG. 2 is a top plan view thereof, the bottom being substantially the same as shown in FIG. 5;

FIG. 3 is a side elevational view of a modified form of the luminaire shown in FIG. 1;

FIG. 4 is a top plan view thereof, as shown in FIG. 3; and

FIG. 5 is a bottom plan view of the luminaire shown in FIG. 3.

I claim:

The ornamental design for a luminaire, as shown and described.
